NAPOLEON J. CARTIER, OF NEW HAVEN, CONNECTICUT.

TOOL-WEDGE.

1,293,332.

Specification of Letters Patent.

Patented Feb. 4, 1919.

Application filed January 29, 1916. Serial No. 75,084.

To all whom it may concern:

Be it known that I, NAPOLEON J. CARTIER, a citizen of the United States, residing at New Haven, in the county of New Haven and State of Connecticut, have invented new and useful Improvements in Tool Wedges, of which the following is a specification.

This invention relates to tool wedges and 10 it consists in the novel features hereinafter described and claimed.

An object of the invention is to provide a wedge of the character indicated which is of simple structure and which when positioned in the end of a tool handle will securely hold the tool in position thereon without excessively splitting or cutting the grain of the wood which constitutes the handle.

20 Another object of the invention is to provide in a wedge of the character indicated means for readily removing the same from the tool without requiring the necessity of injuring the tool by heating the same.

25 A still further object is to provide in a device of the character indicated a wedge of such shape or configuration that it may be easily driven into the wood without danger of the parts of the wedge coming in contact with the sides of eye of the tool and twisting or turning the wedge as it is driven in the wood and furthermore to provide a wedge which when driven into the wood will securely remain therein and will 30 not work loose incident to the use to which the tool may be put.

In the accompanying drawing:—

Figure 1 is a top plan view of the wedge applied to a hammer handle,

0 Fig. 2 is a side view of the wedge.

Fig. 3 is a transverse sectional view of the same.

The wedge is formed from a blank 1 of thin metal preferably Norway iron. The said blank is provided with a straight edge 2 and a curved edge 3. An opening 4 is provided in the blank 1 in the vicinity of the straight edge 2 thereof and at equal distances from the opposite ends of the said

straight edge. The opposite side surfaces 50 of the blank 1 converge toward each other from the straight edge 2 and the said surfaces intersect each other at the curved edge 3 which is thus rendered sharp. In edge elevation the blank 1 is ogee shaped and the 55 said curvature or configuration extends the full length of the blank from the edge 2 to the edge 3.

When the wedge is applied to a tool handle it is driven into the same through 60 the eye of the tool, the edge 3 first entering the handle and the wedge is driven in until the edge 2 is flush with the end of the handle. By reason of the peculiar configuration of the wedge it separates the grain 65 of the wood to an extent to spread the end of the handle and cause the same to firmly seat in the eye of the tool. At the same time the configuration of the wedge is such that it does not cut or mutilate the grain of 70 the wood and thus the presence of the wedge in the handle does not weaken the same. Again by reason of the fact that the edge 3 is devoid of corners or angles there is no possibility of the said edge engaging the 75 walls of the eye of the tool and deflecting the course of the wedge as it is being driven into the handle. Again by reason of the fact that the edge 3 is devoid of angles or corners it does not encounter the walls of the eye of 80 the tool therefore when the tool is subjected to shock incident to use there is no possibility of the force of the attack being transmitted directly to the wedge and dislocating it from its proper position in the handle. In 85 the event that it is desired to remove the wedge from the handle, a nail set may be inserted into the handle and passed into the opening 4 and the said nail set may then be used as a lever for withdrawing the wedge 90 from the handle.

Having described the invention what is claimed is:

1. A tool wedge comprising a blank having its back edge lying in a straight plane 95 and a substantially semi-circular penetrating edge, said blank being wedge shaped in vertical cross-section and ogee shaped in

horizontal cross-section with its sides tapered to form sharp side edges as continuations of said semi-circular penetrating edge.

2. As a new article of manufacture, a tool 5 wedge having a semi-circular, sharpened, penetrating edge and also having a square back edge; the semi-circular, penetrating edge being adapted to make a drawn and smooth cut, and the back edge being ar-

ranged to rest flush with the end of a tool 10 handle when the wedge is driven home therein.

In testimony whereof I affix my signature in presence of two witnesses.

NAPOLEON J. CARTIER.

Witnesses:

P. E. WHALEN,
EUGENE CARTIER.
